CLAIM

The ornamental design for a three dimensional scanning device, as shown and described.

DESCRIPTION

FIG. 1 is a perspective view of a three dimensional scanning device showing our new design;

FIG. 2 is a front view thereof;

FIG. 3 is a rear view thereof;

FIG. 4 is a left side view thereof, and a right side view is a mirror image of the left side;

FIG. 5 is a top view thereof;

FIG. 6 is a bottom view thereof; and

FIG. 7 is a perspective view of the three dimensional device in a closed state.

FIG. 8 is a perspective view of a second embodiment of the three dimensional scanning device;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof; and,

FIG. 15 is a perspective view of the three dimensional scanning device of FIG. 8, shown in a closed state.

(Continued)

In the drawings, the broken lines are for the purpose of illustrating the light area, the socket area, and the switching button area and form no part of the claimed design.
